HARVEY D. BELL, OF FOREST HILLS, NEW YORK.

MECHANISM AND METHOD FOR CUTTING, ASSOCIATING, AND FOLDING SHEETS.

Application filed April 13, 1927. Serial No. 183,280.

The invention relates to new and useful improvements in sheet cutting, associating and folding mechanism and more particularly to such mechanism as applied to fast rotary web printing presses, although the invention has other applications in web and sheet handling machines.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a fragmentary elevation, partly diagrammatic and with certain old parts omitted, illustrating one embodiment of the invention;

Fig. 2 is a vertical transverse section taken through the central part of Fig. 1;

Fig. 3 is a partly diagrammatic elevation of the mechanism of Fig. 2 showing the actuating and timing mechanism for the impaling pins;

Fig. 4 is a fragmentary elevation of the end of one of the folding cylinders of Figs. 3;

Figs. 5 to 10 are diagrams showing various stages of one manner of operating the machine;

Fig. 11 is a diagrammatic fragmentary elevation showing an auxiliary sheet control roller.

This invention is directed to providing a novel and useful sheet cutting, collecting, associating and folding mechanism which is capacitated, amongst other things, to handle a product of extraordinary size, that is a very large number of sheets at high speed; the necessity for this arising, and the invention finding one of its most valuable applications in fast rotary printing presses. By my invention a plurality of running longi-

tudinally folded webs are cut into sheets by a plurality of cutting mechanisms, the sheets then being associated and usually collected also, and thereafter folded as an entirety, and thereby the capacity of a printing press, or other web-using machine is greatly increased.

Furthermore, the mechanism is capacitated to deliver a large variety of lesser products, and to provide different arrangements or associations of the parts of the product with a minimum amount of effort or preparation and of arrangement of the mechanism. For example, if colored webs, or a part web, is run, it may be associated and interfolded in a number of different ways not possible with the usual and known mechanisms.

One of the particular features of my invention is the provision of mechanism for cutting the webs into sheets in sub-multiples of the final product non-simultaneously, the fractional cuttings, distributing and minimizing the shock and strain of cutting. Subsequent association of larger groups of sheets than could be cut at one time is thus possible, this combined sheet group being all folded off together.

In connection with this feature of the invention, improvements are made in the cross folder, especially in the folding-off rollers which cooperate with the folding blade so as to permit the passing of the lead end of an extremely thick group of associated sheets, and the successive folding off of this group at very high speed without choking or misfolding, and also providing a smooth and clean leaving action for the folding blade after the folding rollers have gripped the product.

In the exemplary and present preferred embodiment, broadly defined, two formers are employed, which usually receive the respective halves of a slit web, or any number of running webs associated at the head of the former in the usual manner. Angle bars may likewise be employed if so desired, but usually will not be necessary.

The associated and longitudinally-folded running webs are led from one of the formers to a cross-folding cylinder, which is provided with cutting means. In operative relation with the cross-folding cylinder is a cylinder which cooperates to cut off the sheets, and it

may be used optionally to collect one group of sheets, which are then associated with the next group of cut-off sheets upon the cross folding cylinder.

5 The associated and longitudinally folded running webs from the other former go primarily to a cutting and transfer cylinder, and cooperating with this transfer cylinder is another cutting cylinder, which also may 10 be used optionally as a collecting cylinder. When so used the first group of sheets cut from the running webs by these cylinders is collected upon the collecting cylinder, and is then associated with a second cut-off group 15 of sheets upon the transfer cylinder. The sheets from the transfer cylinder, whether collected or not, are transferred and associated with, the sheets upon the cross-folding cylinder (which may have been collected or 20 not as already described).

The entire group of sheets is then folded off from the cross-folding cylinder in the usual manner, except that provisions are made for handling the very large product 25 which this mechanism renders possible. For this purpose, the forward or right-hand folding-off roller is lowered as a new lead end of the associated sheets comes by to permit clearance for the lead or head end of 30 the sheets and for the impaling pins. The folding rollers are also longitudinally grooved so as to have a clinching or gripping action upon the fold as the sheets are thrust between them by the folding blades.

35 My invention provides, as stated, for timing the sheet-cutting operations non-concurrently and this is effected in the illustrated embodiment by placing the two cylinders effecting the cuts of the respective webs in different angular relations, that is, the plane passing through the shafts of one of the pairs of cylinders is non-parallel to the similar plane of the other pair of cylinders.

40 It will be understood that the foregoing general description, and the following detailed description as well, are explanatory and exemplary of the invention but are not restrictive thereof.

45 Referring now in detail to the embodiment 50 of the invention illustrated by way of example in the accompanying drawings, the invention is considered applied to a fast rotary printing press having a plurality of perfecting units, the full-width, perfected 55 webs from the various units being brought together at the rollers at the head of the two formers, which latter are fragmentarily shown in Fig. 1. Slitting means for the webs are provided, and may be located at and between the formers in a well-known manner.

50 Former 1 has the usual forming rolls 2 and 3 and guide rolls 4 and 5, the running half web being associated and longitudinally folded at this point. They pass thence about 60 the gripping and alining roller 6 which may

be of the usual form. For effecting register or alinement of the web leads and sheets, as shown, shaft 7 of this roller is mounted in arms 8 and 9, which are pivoted upon a shaft 10 carried on the press frame. The screw-threaded adjustment 11 is provided whereby the position of the roller 6 may be varied to register the web leads and sheet heads with the subsequently operating mechanism.

65 The cross folding cylinder 25 may be of 70 usual or other suitable construction and is shown with its shaft 26 journaled at 27 in the side frames of the press. The cylinder is shown provided with two folding blades 28 and 29, mounted diametrically opposite on the 75 cylinder in a well-known manner. The operating mechanism for the folding blades is not shown, and may be of the standard "Husby" type used on the Goss printing press.

80 The folding cylinder 25 as embodied, is provided with two sets of impaling pins, one set 85 31 being mounted upon corresponding arms 32, fixed on a shaft 33, journaled in the heads of the folding cylinder, the pins being projectable and retractable through holes near 90 the cutting block 57 so as to take and release the sheet heads in the usual manner.

95 The shaft 33 projects through the cylinder end, and is provided with actuating and timing means, comprising an arm 34 fixed to the shaft 33, and provided with a cam-roller 35, running in the groove cam 36, journaled loosely on the cylinder shaft 26. The timing device comprises an arm 39, fixed to the hub 100 40 of the cam 36. This arm 39 is provided at its outer end with an arcuate slot 41, through which projects a clamping bolt 42 which is screw-threaded into the machine frame, to hold the cam in proper timing position.

105 The other set of impaling pins 49 is of similar construction, being mounted upon a series of arms 50, fixed to a shaft 51, journaled diametrically opposite in the folding cylinder. The end of this shaft likewise projects from the cylinder end, and fixed to the shaft is an arm 52, carrying a cam-roller 53, which also runs in the grooved actuating and timing cam 36.

110 The grooved cutting blocks 57 and 58 are 115 oppositely mounted in the folding cylinder in the proper contiguous relations to the impaling pins, and their cooperating cutting blades.

115 The cutting cylinder 69, which cooperates with the folding cylinder, has its shaft 70 120 mounted in bearings 71 in the press frame. This cylinder is provided with a cutting blade 72, which cooperates successively with the cutting grooves 57 and 58 in the cross-folding cylinder, to cut off two groups of sheets for 125 each revolution of the folding cylinder, the cutting cylinder making two revolutions for one of the folding cylinder. The optionally utilized collecting means comprises a set of impaling pins 75 reciprocable in holes in the 130

collecting cylinder contiguous with the cutting blade 72. These impaling pins are preferably mounted on a corresponding series of arms 76, fixed on a shaft 77, journaled in the 5 ends of the cutting cylinder.

The actuating means comprises an arm 78, fixed to the end of the shaft 77, which projects from the head of the cylinder 69. This arm is provided with a cam-roller 79, running in the groove cam 80, which is mounted 10 on the shaft of the cylinder 69, and may be provided with timing means of any suitable kind, as for instance, like that already described for the impaling pins of the cross-folding cylinder. When the cylinder is not used for collecting, the impaling pins are retracted and silenced in any suitable manner, as for instance by sliding the arm 78 along the shaft 77 and thereby moving the cam 20 roller 79 out of the cam 80.

Referring now to the other series of webs, the associated half webs run down and are longitudinally folded by, the former 100, forming rolls 101 and 102, and guiding rollers 25 103 and 104 cooperating therewith in the usual manner. A guiding and registering roller 106 is provided for these webs, which may be similar or the same as the roller 6. The shaft 107 of this roller is mounted in 30 arms 108, pivoted at 109 upon the machine frame, and furnished with a screw-thread adjustment similar to screw thread adjustment 11, whereby the roller 106 may be raised and lowered, as may be necessary to register the 35 lead end of the sheets with those from the other mechanism.

The transfer cylinder 121 has its shaft 122 mounted in journal bearings 123 in the machine frame. These journal bearings are 40 preferably provided with means for positioning the transfer cylinder toward and away from the cross-folding cylinder 25 for products of different thicknesses. In the embodied form of said means, the journal boxes 124 are slidably mounted in guides 125 upon the machine frame, and are provided with screw-threaded adjusting means 126.

The transfer cylinder 121 is provided with 50 grooved cutting blocks 135 and 136 diametrically opposite each other. Adjacent to and cooperating with the cutting block 135 is a series of impaling pins 137, which are fixed upon corresponding arms 138, which are fixed to a shaft 139, journaled in the heads of the 55 transfer cylinder 121. These pins are in position relatively to the cutting block 135 so as to take the heads or lead of the cut-off webs. The actuating mechanism therefor comprises an arm 140, fixed to the end of the shaft 139, 60 exteriorly to the cylinder, the arm carrying a cam-roll 141, which runs in a groove cam 142, loosely mounted upon the shaft 122 of the cylinder.

The other set of impaling pins 149, cooperates in like manner with the cutting groove

136. These pins are fixed to a corresponding series of arms 150, fixed to a shaft 151, journaled in the heads of the cylinder. An actuating arm 155 is fixed to the external end of the shaft 151 and is provided with a cam-roller 156, running in the groove cam 142. 70

The timing means in this mechanism comprises an arm 159, fixed to the hub 160 of the groove cam 142. This arm 159 is provided at its outer end with an arcuate slot 161, 75 through which passes a clamping screw 162, screw-threaded into the end of an arm 163, fixed to and extending outwardly from the journal box 124. This construction permits of the adjustment or positioning of the transfer cylinder 121 relatively to the cross folding cylinder 25 without disturbing the operating and timing relation of the cam 142.

Copperating with the transfer cylinder is a cutting cylinder 169, which has its shaft 85 170 journaled at 171, in the side frames of the press. This cylinder is provided with a cutting knife 172, which cooperates successively with the cutting groove blocks 135 and 136. The cutting cylinder makes two revolutions to one of the transfer cylinder, and the transfer cylinder and the cross-folding cylinder make revolution for revolution. 90

The optionally used collecting means comprises a set of impaling pins 173, reciprocably mounted in the cutting cylinder, adjacent to the knife 172 to take the web leads. These pins are pivotally connected to corresponding series of arms 176, which are fixed to a shaft 177, journaled in the heads of the 100 collecting cylinder. Fixed to the projecting external end of shaft 177 is an actuating arm 178, provided with a cam-roller 179, which runs in a cam groove 180. Cam 180 is loosely mounted upon the cylinder shaft 177 and is 105 held and timed by any suitable mechanism, such as that previously described for the other cylinders. When this cylinder does not collect the impaling pins may be retracted and silenced in any suitable manner, as by slipping the arm 178 along shaft 177, and thereby removing the cam-roller 179 from the cam 180. 110

For the purpose of causing the cuts made by the two pairs of cylinders to be made non-concurrently, cylinder 169 is placed in a different angular relation to the transfer cylinder 121 than that of cutting cylinder 69 to the cross-folding cylinder 25, as will be clear from Figs. 1 and 2. Thus the cuts in one 120 web are made between the cuts in the other web without disturbing the timed relation of the webs and sheets. 125

Referring now to the folding-off mechanism, the folding blades 28 and 29 cooperate with folding-off rollers 199 and 200. These rollers are not perfectly cylindrical but are longitudinally recessed, or broadly grooved, as shown best in Fig. 2 at the contiguous parts of the rollers, the rollers being shown 130

respectively and longitudinally-disposed depressed parts 201 and 202 so timed as to be opposite each other when the folding blade, as shown at 29, is making the fold. This permits the free entry between the rollers of a very large group of associated sheets, the rollers then have a clinching or clamping action in addition to their rotary forwarding movement, and thereby firmly grasp and hold 10 the cross-folded sheets without slippage.

The head roller 199 is also mounted to move toward or away from the cross-folding cylinder 25, so as to give clearance for the head of the on coming group of sheets and for 15 the impaling pins, and also to provide a smooth leaving action for the folding blade. As embodied, the shaft or pintles 207 of this roller are mounted in arms 208, which are preferably pivoted at 210 concentrically with 20 the shaft 212 of the roller 200.

While the mechanism can be run in a variety of ways to provide a variety of products, the operation of the machine when collecting upon both of the cutting cylinders 25 so as to give a maximum product is exemplarily shown in Figs. 5 to 10. It will be understood, however, that one half of the mechanism and the webs on one side could be run without those on the other side, or either 30 of the cutting cylinders could be used to collect, or neither or both, as desired.

In the illustrated exemplary manner of running the machine (shown in Figs. 5 to 10) in Fig. 5 both cutting cylinders 69 and 169 are shown taking the leads of the two webs, or slit half webs, which the impaling pins on the cylinders have secured, just as a previous cut had been made. The previous sheets are omitted from all these figures for 40 the sake of clearness. In Fig. 6 the leads of both the associated and longitudinally inter-folded webs are shown collected upon the corresponding cutting cylinders 69 and 169, and in Fig. 7 the sheets collected upon 45 these two cylinders are being severed from the respective webs, and new web leads thus formed are taken, respectively, by the impaling pins upon the cross-folding cylinder 25 and the transfer cylinder 121.

In Fig. 8 the association of the sheets on the transfer cylinder 121 with the collected sheets previously on the cross-folding cylinder 25 is shown, the impaling pins of the transfer cylinder 121 being retracted and the 55 sheet heads being taken upon the impaling pins of the cross-folding-cylinder 25. To facilitate this transfer action, the impaling pins upon the cutting and collecting cylinder 69 and upon the transfer cylinder 121 are in 60 register with each other, and the impaling pins upon the cutting and collecting cylinder 169 and the cross-folding cylinder 25 are in register with each other. Thus during the 65 transfer of the sheets, the impaling pins of the cylinder 121 momentarily pass into the

holes made in the sheet heads by the impaling pins on the cylinder 69 and hold the sheets, and the impaling pins of the cylinder 25 enter the holes made in the sheet heads by the impaling pins of the cylinder 169, which effects 70 an easy, certain and accurate transfer and association of all the sheets without unnecessary puncturing of the sheets.

In Fig. 9 the head of all of the associated sheets is shown passing the folding-off rollers 199 and 200, the roller 199 being lowered to 75 permit clearance as already described and in Fig. 10 the final folding off of the entire group of associated sheets is shown.

In Figs. 9 and 10 is shown the beginning so of the next operation upon the web leads, similar to the showing in Figs. 5 and 6.

The capacity to relatively position the folding and transfer cylinders closer together or farther apart is very useful in connection 85 with handling groups of sheets of different thicknesses. This capacity is also useful in controlling the sheet group during the handling thereof by the two cylinders and particularly just prior to and at the folding off 90 of the group of sheets. With many kinds of work this control will be found entirely adequate, including the control of the tail end of the sheet group just prior to and while folding off. In accordance with one feature of 95 the invention, however, additional means may be provided cooperating to control the handling of the sheet group upon the folding cylinder. As embodied and at present preferred, a pressure roller 225 cooperates with the folding cylinder preferably quite close to the common point of the folding cylinder and transfer cylinder, as shown in Fig. 11. This roller is made positionable to and from the folding cylinder, and for this purpose, the 100 roller shaft 226 is mounted in bearings 227, carried on supports 228. These supports are preferably longitudinally slideable in supporting members 229 at either side of the press frame. To effect the positioning of the roller to and from the folding cylinder, supporting rods 228 are screw-threaded, and are provided with nuts 230 and 231, or with any other suitable position determining means.

It will be clear from the foregoing that a mechanism has been provided realizing the objects and advantages herein set forth, together with other objects and advantages; and that departures may be made from the exact constructions shown and described 120 without departing from the principles of the invention and without sacrificing its chief advantages.

What I claim is:—

1. A sheet cutting and handling mechanism 125 including in combination means for traveling webs by a plurality of paths from a machine operating thereon, devices for cutting a web into sheets in one of said paths, devices for non-simultaneously cutting a web at corre- 130

sponding sections into sheets in another path, and means for interfolding the sheets from both paths.

2. A sheet cutting and handling mechanism including in combination means for traveling webs by a plurality of paths from a machine operating thereon, devices for cutting a web into sheets in one of said paths, devices for non-simultaneously cutting a web at corresponding sections into sheets in another path, sheet collecting means located between one of the cutting devices and the interfolding means, and means for interfolding the sheets from both paths.

15 3. A sheet cutting and handling mechanism including in combination means for traveling webs by a plurality of paths from a machine operating thereon, devices for cutting a web into sheets in one of said paths, devices for non-simultaneously cutting a web at corresponding sections into sheets in another path, optionally operable sheet collecting means located between one of the cutting devices and the interfolding means, and means for interfolding the sheets from both paths.

20 4. A sheet cutting and handling mechanism including in combination means for longitudinally folding a plurality of webs traveling by different paths, devices for cutting a folded web at corresponding sections into sheets in one of said paths, devices for non-simultaneously cutting a folded web into sheets in another path, and means for interfolding the sheets from both paths.

25 5. A sheet cutting and handling mechanism including in combination means for longitudinally folding a plurality of webs traveling by different paths, devices for cutting a folded web into sheets in one of said paths, devices for non-simultaneously cutting a folded web at corresponding sections into sheets in another path, means for collecting the longitudinally folded sheets between one of the cutting devices and the interfolding means, and means for interfolding the sheets from both paths.

30 6. A sheet cutting and handling mechanism including in combination means for traveling webs by a plurality of paths from a machine operating thereon, devices for cutting a web into sheets in one of said paths, devices for non-simultaneously cutting a web at corresponding sections into sheets in another path, means for associating successively cut sheets in one of said paths and forwarding the associated sheets, and means for interfolding the sheets from both paths.

35 7. A sheet cutting and handling mechanism including in combination two formers adapted to longitudinally fold the two halves of slit webs, a cross folding cylinder, and sheet cutting means for each half web between said formers, said sheet cutting means operating non-simultaneously to cut the webs

at sections equi-distant from their leading ends.

40 8. A sheet cutting and handling mechanism including in combination a folding cylinder, a collecting cylinder optionally operable to collect sheets on the folding cylinder and a transfer cylinder optionally operable to supply sheets directly to the folding cylinder in association with the sheets thereon.

45 9. A sheet cutting and handling mechanism including in combination a folding cylinder, a collecting cylinder optionally operable to collect sheets on the folding cylinder and means for supplying other sheets to the folding cylinder including a transfer cylinder and a cooperating optionally operable collecting cylinder.

50 10. A sheet cutting and handling mechanism including in combination a folding cylinder, a collecting cylinder optionally operable to collect sheets on the folding cylinder, and means for supplying other sheets including a transfer cylinder for supplying sheets directly to the folding cylinder and a collecting cylinder optionally operable to supply sheets to the transfer cylinder.

55 11. A sheet cutting and handling mechanism including in combination two formers adapted to longitudinally fold two halves of a slit web, a cross-folding cylinder, a cylinder cooperating with the folding cylinder to cut sheets from one half-web, other sheet cutting means for cutting sheets from corresponding portions of the other half-web, and means for supplying the sheets from said other sheet cutting means to the cross folding cylinder to be folded thereby.

60 12. A sheet cutting and handling mechanism including in combination two formers adapted to longitudinally fold two halves of a slit web, a cross-folding cylinder, a cylinder cooperating with the folding cylinder to cut sheets from one half-web, other sheet cutting means for cutting sheets from corresponding portions of the other half-web, and means for supplying the sheets from said other sheet cutting means into association with the sheets on the cross folding cylinder to be interfolded together.

65 13. A sheet cutting and handling mechanism including in combination two side by side formers adapted to longitudinally fold two halves of a slit web a cross-folding cylinder, a cylinder cooperating with the folding cylinder to cut sheets from one half-web, optionally operative sheet collecting means on said cooperating cylinder, other sheet cutting means for cutting sheets from corresponding portions of the other half-web, and means for supplying the sheets from said other sheet cutting means to the cross-folding cylinder to be folded thereby.

70 14. A sheet cutting and handling mechanism including in combination a cross-fold-

ing cylinder, a cylinder cooperating therewith to cut sheets from a web, optionally operating means for collecting sheets on said cooperating cylinder, a second cutting cylinder, a transfer cylinder cooperating therewith to cut sheets from a web, and means for transferring sheets from the transfer cylinder to the cross-folding cylinder.

15. A rotary folding mechanism including 10 in combination a folding cylinder having a folding blade, a pair of folding off rollers cooperating with the folding blade, and means permitting the forward folding off roller to be moved away from the cylinder 15 to pass the head of a group of sheets on the cylinder.

16. A rotary folding mechanism including 20 in combination a folding cylinder having a folding blade, a pair of folding off rollers co-operating with the folding blade, and means permitting the forward folding off roller to be moved away from the cylinder in an arc concentric with the other roller to pass the head of a group of sheets on the cylinder.

25 17. The method of producing a large cross-folded product from a plurality of webs which comprises cutting one group of sheets from webs, non-simultaneously cutting another group of sheets from corresponding 30 portions of other webs, associating said groups of sheets and folding them off together.

35 18. The method of producing a large cross-folded product which comprises severing sheets from corresponding portions of a plurality of webs non-simultaneously in sub-multiple groups, associating the sheet groups so produced, and folding them off together.

40 19. The method of producing a large cross-folded product which comprises associating the leading ends of a plurality of webs, non-simultaneously severing each web to form sheets, and folding off said sheets together.

45 20. The method of producing a large cross-folded product which comprises non-simultaneously severing a plurality of webs at corresponding sections to form sheets of equal length, associating said sheets and folding them off together.

50 21. The method of producing a large cross-folded product which comprises non-simultaneously severing corresponding sections from a plurality of webs to form sheets, associating each sheet so formed with the succeeding leading portion of its respective web, non-simultaneously severing said leading portions of the webs to form a plurality of groups of associated sheets, associating said groups of sheets and folding them off together.

55 22. The method of producing a large cross-folded product which comprises non-simultaneously severing a plurality of webs at sections equi-distant from the leading ends of the webs, associating the sheets so formed and 60 folding them off together.

23. A sheet cutting and handling mechanism including in combination means for traveling webs by a plurality of paths from a machine operating thereon, means for joining the leading ends of the webs, devices for cutting a sheet from the leading end of one web and devices for non-simultaneously cutting a sheet from the leading portion of a web in another path. 70

24. A sheet cutting and handling mechanism including in combination means for traveling webs by a plurality of paths from a machine operating thereon, means for joining the leading ends of the webs, devices for cutting a sheet from the leading end of one web and devices for non-simultaneously cutting a sheet from the leading portion of a web in another path and means for interfolding the sheets from both paths. 75

25. A sheet cutting and handling mechanism including in combination two formers adapted to longitudinally fold the two halves of slit webs, a cross folding cylinder, sheet cutting means for each half-web between said formers adapted to non-simultaneously cut the webs at sections equidistant from their leading ends, and means for interfolding the sheets from each half-web. 85

26. The method of producing a large cross-folded product which comprises joining the leading ends of a plurality of webs on the periphery of a rotating cylinder, non-simultaneously severing each web to form an associated group of sheets of equal lengths, the time interval between the severings of the respective webs comprising a relatively small fraction of the angular travel of the cylinder, and folding off the group of sheets together. 95

27. A sheet cutting and handling mechanism including in combination means for traveling webs by a plurality of paths from a machine operating thereon, a pair of co-operating cutting cylinders for cutting a web into sheets in one of said paths, a pair of cooperative cutting cylinders for cutting a web into sheets in another path, said respective pairs of cooperating cutting cylinders being adapted to cut at relatively slightly different times whereby the cutting of the sheets in the different paths is non-simultaneous, and means for interfolding the sheets from both paths. 105

28. A sheet cutting and handling mechanism including in combination means for traveling webs by a plurality of paths from a machine operating therefrom, a pair of co-operating cutting cylinders for cutting a web into sheets in one of said paths, a pair of cooperative cutting cylinders for cutting a web into sheets in another path, the angular relation between one pair of cutting cylinders being slightly different from the corresponding angular relation of the other pair of cutting cylinders, whereby the cut- 120

125 130

ting of the sheets in one path occurs non-simultaneously with the cutting of the corresponding sheets in the other path.

29. A sheet cutting and handling mechanism including in combination a folding cylinder, a collecting cylinder optionally operable to collect sheets on the folding cylinder and a transfer cylinder optionally operable to supply sheets directly to the folding cylinder in association with the sheets thereon, and means for varying the space between the transfer and folding cyl-

inders to accommodate products of different thicknesses.

30. A rotary folding mechanism including in combination a folding cylinder having a folding blade, a pair of folding-off rollers cooperating with the folding blade, the forward folding off roller being positionable farther from the cylinder than the other of said rollers.

In testimony whereof, I have signed my name to this specification.

HARVEY D. BELL.
